UNITED STATES PATENT OFFICE

JOSEPH VAN ACKEREN, OF O'HARA TOWNSHIP, ALLEGHENY COUNTY, PENNSYLVANIA,
ASSIGNOR TO THE KOPPERS COMPANY OF DELAWARE, A CORPORATION OF DELA-
WARE

COKE OVEN APPARATUS

Application filed January 28, 1930. Serial No. 423,930.

My invention relates to coke-oven apparatus and particularly to means for conducting and collecting the products of distillation from coke ovens.

5 An object of my invention is to provide a simple and convenient means for connecting the collecting main of the coke-oven battery to the ascension pipes of the latter in such manner as to permit relative movement there-
10 between.

A further object of my invention is to provide means for connecting the collecting mains of coke-oven batteries to ascension pipes in such manner as to permit a unitary
15 rigid construction of the latter.

A still further object of my invention is to provide an ascension pipe for coking retort ovens that is of simple and rigid construction whereby its parts are not subject to deteriora-
20 tion by reason of relative movements there-
between.

In the construction of coke-oven apparatus prior to the present invention, it has been the practice to provide a rigid connection be-
25 tween the collecting main and the return bend of the ascension pipe. Inasmuch as varia-
30 tions in relative temperatures of the series of communicably-connected parts comprising the coke oven, the ascension pipe and the col-
lecting main tend to cause relative movements of these parts, the straight vertical portion of the ascension pipe has been constructed in two parts, with a flexible connection therebetween to provide for the necessary relative move-
35 ment.

Difficulty has been experienced in main-
taining the structure described above because of the severe strains between the ascension pipe and the collecting main, tending, under
40 certain circumstances, to rotate the collecting main to which the upper portion is connected and, under other circumstances, the strains have tended to deflect the ascension pipe from its vertical position. Under these conditions, 45 it has been practically impossible to maintain gas-tight joints between the sections of the ascension pipes.

Leakage of air into the ascension pipes around the joints caused combustion therein and the upper sections were not protected
50

from such combustion as were the lower sec-
tions with their refractory linings. This combustion caused bulging or distortion of the upper sections and further increased the tendency to leakage. Also, carbon deposits
55 near the joints caused the lifting of the upper sections.

All of these conditions caused relatively high maintenance costs for material and labor in attempting to maintain gas-tight connec-
60 tions between the ovens and the collecting main. Cement or other materials were used substantially continuously to keep the joints in proper condition.

In accordance with the present invention, it is proposed to provide a flexible connection between the collecting main and the ascension pipe whereby the latter may be of rigid unitary construction, with the entire vertical section protected from high temperatures in
70 the manner heretofore usual with the lower section only. The flexible connection be-
75 tween the ascension pipe and the collecting main is of such nature as to permit the relative movements that occur by reason of varia-
tions in relative temperatures of the connect-
ed parts.

Such flexible connection prevents the trans-
mission of forces heretofore caused by move-
ments of the connected parts and, according-
80 ly, the strains to which the ascension pipe has previously been subjected are substantially entirely eliminated. The expense in main-
taining the ascension pipes has been corre-
spondingly diminished.
85

My invention will be described in connec-
tion with the accompanying drawings, in which

Figure 1 is a view in transverse vertical section of a portion of a coke-oven embody-
90 ing my invention;

Fig. 2 is a view, partially in elevation and partially in section, of an ascension pipe hav-
ing two sections; and

Fig. 3 is an enlarged view, partially in ele-
vation and partially in section, of a portion of the apparatus of Fig. 1.
95

Referring particularly to Fig. 1, a coke-
oven battery 1, only a portion of which is shown, comprises a foundation 2, a side wall
100

3 and a roof or top 4, through which extend a charging hole 5 for a coking chamber 6, and a gas offtake opening 7 at one end of the coking chamber. A regenerator 8 is beneath the coking chamber 6. The battery is also provided with a producer gas main 9, a coke-oven gas main 10 and a waste gas main 11 for conducting products of combustion to the usual stack, not shown.

- 10 The battery is provided with the usual buckstays 12 for bracing the side walls of the battery and which support a framework 13 at the top thereof and upon which is mounted a collecting main 14. An ascension pipe 15 that 76
15 is mounted upon the top 4 and is connected to the gas offtake opening 7 is flexibly connected to the collecting main 14 in a manner to be described.

An ascension pipe 16 of the prior art type 20 is shown in Fig. 2. The lower section 17, connected to the offtake opening of a coke oven, is of metal that is provided with a lining 18 of refractory material such as ramrite. The upper section 19 telescopes with the lower section 25 and asbestos rope or other packing or refractory material indicated at 20 provides a flexible seal between the sections.

Leakage of air occurred at this junction of the sections and the resulting combustion 30 caused damage of the unprotected upper section 19 as described above and it has been found to be substantially impossible to maintain satisfactory operating conditions even with constant maintenance.

35 The upper section 19 is rigidly connected to a return bend 21 in which is located a spray 22. The return bend 21 is rigidly connected by a casting 23 to a collecting main 24. A valve 25 under the spray 22 operates as a seal when closed by the operation of a weight-ed arm 26.

Reference may now be had to Fig. 3, in 40 which the details of construction of the ascension pipe 15 and its associated parts are illustrated. The ascension pipe 15 comprises a vertical section 27 that is rigidly connected to the oven top 4 by refractory cement, indicated at 28. The section 27 comprises a metal pipe 29 having an inner lining 30 of refrac-tory material, such, for example, as ramrite.

Secured to the upper end of the section 27 is a return bend 32, the lower outer end of which is provided with an annular flange 33. The return bend 32 is connected to the collecting main 14 by means of a curved pipe 34, having a vertical section 35 which telescopes the lower end of the return bend 32. The space between the telescoping portions of these connected members is filled with asbestos rope 36, which rests upon the flange 33. The remainder of the space is filled with carbon pitch, the section 35 of the pipe 34 flaring outwardly to provide an annular space to receive this material.

65 While other plastic materials may be used

for sealing the space between the telescoping parts of the return bend and the pipe 34, carbon pitch is especially suitable for this purpose because it is subjected to a temperature of about 80° to 90° C., since it is located in the area of the spray of ammonia liquor for cooling the gas before it enters the collecting main. Ammonia liquor is supplied to the return bend 32 by means of a pipe 37. Within the temperature range referred to above, carbon pitch is always sufficiently plastic to permit relative movements of the telescoping pipes by reason of varying temperature conditions.

At the temperatures to which the flexible connection is subjected, the carbon pitch maintains a gas-tight connection between the relatively movable parts and there is no leakage of gas by reason of such relative movements. No strains are transmitted between the ascension pipe and the collecting main 14.

The usual seal for preventing the flow of gas from the collecting main into the ascension pipe 15 when the oven to which the latter is connected is not charged is provided by a pivotally-mounted cup-shaped valve member 39 that may be operated by a lever 40 and is held in position by a weight 41. An annular flange 42 projects below the rim of the cup-shaped member 39 when the latter is in the position illustrated and the ammonia liquor accumulates in the latter to constitute a liquid seal for the pipe 34.

Ascension pipes constructed in accordance with my invention are cheaper in construction and require much less maintenance than those formerly used. The provision of a protective refractory lining for the entire vertical section of the standpipe insures that the entire section is subjected to substantially uniform operating conditions and the deterioration of the ascension pipe will be substantially eliminated in all portions of the vertical section.

The foregoing and other advantages will 110 be apparent to those skilled in the art relating to the construction and operation of coking retort ovens. My invention may be embodied in various forms and it is not to be limited to the preferred embodiment 115 shown and described herein except as expressed in the appended claims.

I claim as my invention:

1. Coke oven apparatus comprising a collecting main, and an ascension pipe having a vertical portion and a return bend rigidly connected to said vertical portion and flexibly connected to said collecting main.

2. Coke oven apparatus comprising an ascension pipe having a vertical portion and a return bend rigidly mounted thereon, a collecting main and means for yieldingly connecting said return bend to said collecting main.

3. Coke oven apparatus comprising an

ascension pipe having a vertical portion and a return bend rigidly mounted thereon, a collecting main and means for yieldingly connecting said return bend to said collecting main, said means comprising a member for telescopic connection to said return bend and plastic material between said member and said return bend.

4. Coke oven apparatus comprising an ascension pipe having a single unitary vertical portion and a return bend rigidly connected thereto, a collecting main and means for yieldingly connecting said collecting main to said return bend for movement relative thereto.

5. Coke oven apparatus comprising an ascension pipe having a single unitary vertical portion and a return bend rigidly connected thereto, a collecting main, and means for yieldingly connecting said collecting main to said return bend for movement relative thereto, said means comprising a member telescoping with said return bend and plastic material for connecting the telescoping parts of said member and said return bend.

6. Coke oven apparatus comprising a collecting main, and an ascension pipe having a single upright portion that is rigidly mounted in position and a return bend rigidly connected to said vertical portion and flexibly connected to said collecting main for communication therewith and relative movement therebetween.

35 7. Coke oven apparatus comprising a collecting main, and an ascension pipe having a single upright portion that is rigidly mounted in position and a return bend rigidly connected to said vertical portion and flexibly connected to said collecting main for communication therewith and relative movement therebetween, said collecting main having a member for telescoping a portion of said return bend and plastic material for sealing the space between the telescoping portions.

8. Coke oven apparatus comprising an ascension pipe consisting of a single vertical section and a return bend rigidly connected thereto, and a collecting main flexibly and communicably connected thereto.

50 9. Coke oven apparatus comprising an ascension pipe having a sprayer for liquid, a collecting main, and means comprising a flexible joint of plastic material for communicably connecting said pipe and said main, said plastic material being beneath said sprayer whereby the temperature of said plastic material is modified by said liquid.

10. Coke oven apparatus comprising an ascension pipe, a collecting main, and means comprising a return bend having a sprayer for liquid therein and a flexible joint of plastic material beneath said sprayer for

communicably connecting said pipe and said main, the temperature of said plastic material being controlled by the liquid from said sprayer.

In testimony whereof, I have hereunto subscribed by name this 24th day of January, 1930.

JOSEPH VAN ACKEREN.
